ANTENNA ROTATOR REMOTE CONTROL HOUSING

Giacinto C. D'Ercoli, Chicago Heights, Ill., assignor to
Consolidated Electronics Industries Corp., a corpora-
tion of Delaware

Filed June 5, 1964, Ser. No. 80,302

Term of patent 14 years

(Cl. D26—13)

FIG. 1

FIG. 2

FIG. 3

FIG. 4

FIG. 5

FIG. 1 is a perspective view of an antenna rotator remote control housing, showing my new design;

FIG. 2 is a right side elevational view;

FIG. 3 is a top plan view;

FIG. 4 is a rear elevational view; and

FIG. 5 is a bottom view of the housing.

I claim:

The ornamental design for an antenna rotator remote control housing, substantially as shown.
